UNITED STATES PATENT OFFICE.

A. CLARKE FELLOWS, OF TROY, NEW YORK.

COLLAR.

SPECIFICATION forming part of Letters Patent No. 284,829, dated September 11, 1883.

Application filed November 28, 1882. (Model.)

To all whom it may concern:

Be it known that I, A. CLARKE FELLOWS, a citizen of the United States, residing at Troy, New York, have invented new and useful Improvements in Collars, of which the following is a specification.

The object of this invention is to provide a reversible garrote or standing collar of novel construction, in which either one of the longitudinal edges of its outer side or ply can be brought uppermost, whereby, after the collar has been worn and the top edge becomes bent or soiled, said edge can be turned down and the corresponding opposite edge brought in position to constitute the top edge of the collar.

My invention is clearly illustrated in the accompanying drawings, in which—

Figures 1 and 3 represent the two plies, which are adapted to be stitched together, so as to form the band portion of the collar. Fig. 2 represents the outer face ply, which is designed to be stitched to the plies, as shown in Figs. 1 and 3. Fig. 4 shows the partly-finished collar, the plies being unattached at one end. Fig. 5 shows the finished collar, and Fig. 6 shows the collar slightly varied in form.

A indicates the inner side piece or ply of the collar, which is cut in the form of an ordinary standing collar. This ply can be either made straight or curved, and is provided with the usual tabs or ends, A', for button-holes, by means of which the collar can be fastened to a shirt. The upper corners of this piece can be either rounded or angular, and the ends A' made long or short, according to the space to be left at the front after the collar has been buttoned on the shirt.

B refers to a supplemental outer ply, which is substantially equal in length to the length of that portion of the inner ply, A, which is between the points x (indicated in Fig. 1) on the latter, and has at each end its two corners made either angular or rounded, or rounded and angular, as illustrated in Fig. 2. A second outer ply, C, is also provided, which is substantially the counterpart of the ply A just described, said second outer ply being shown in Fig. 3 with its upper corners rounded, so as to match the rounded corners of the supplemental ply B, as will be hereinafter more particularly explained. These two counterpart outer plies,

A and C, are stitched together, and also stitched to the ply B, in the following manner: The ends and lower edges of the outer plies, A and C, are stitched together, and one of said plies is stitched along the edge to one half of the ply B, while the other outer ply is stitched in like manner to the remaining half of said ply B, as illustrated in Fig. 4, in which these several plies are left unattached at one end of the collar, so as to indicate the way in which the plies are placed together preparatory to stitching.

It will now be seen that the ply B, which constitutes the outer face portion of the collar, is backed or lined by a portion of each one of the plies A and C, and that it is joined at its ends to the ends of said plies at the points x and y. (Respectively indicated in Figs. 1 and 3.)

In order to prevent the collar from wrinkling while being laundered, and also to enable the part B to be readily and accurately turned about a central longitudinal line, so as to bring its outer face on either side of the collar, a line of stitching, D, is run from end to end of the collar through the plies A and C, said line running between the points y y on ply C, so that said line shall be formed adjacent to the middle of the ply B.

It will be seen that after the collar has been finished it will present the appearance shown in Fig. 5, in which one edge of the part or ply B constitutes the upper edge of the collar, while the lower portion of the said ply below a line taken longitudinally through the same constitutes a flap, under which the band or strap portion of a necktie can be placed, and hence concealed, so that only the bow or body of the tie will be visible, and the tie prevented from slipping up on the collar. As soon as this upper edge of the collar becomes soiled, the collar can be reversed by simply reversing or turning the ply B over upon the opposite side of the collar, so as to bring the remaining edge of ply B uppermost. In such case the lower portion of the collar, previously worn on the inside or next to the neck, will be worn outside; but as such portion is concealed by the flap, it will not detract from the appearance of the collar.

The ply B can be made with its four corners either rounded or angular, or with two angular and two rounded, as indicated in Fig. 2, so

that by reversing the collar in the manner hereinbefore described different styles of collar can be obtained.

It will be seen that the corners of the plies A and C are cut to match the ply B, to which said plies are secured, and it will be evident that either a high or a low collar can be obtained by making one portion of the ply B at one side of a line between points z z wider than the remaining portion, whereby by reversing the collar its height can be varied. Each or any of the plies can be duplicated, or as many extra plies added as may be desired, and the end fastening-tabs can be made long or short, so as to make a collar either open or closed at the front.

In Fig. 6 one edge of ply B is shown scalloped. In this collar the ply is not intended to be reversible, although the construction is the same as those above described, excepting the scalloped edge, this latter portion being adapted to form a flap for holding down the tie.

Heretofore reversible standing collars have been known; but, as I am aware, no such collar has heretofore been made in the manner herein described and shown.

Having thus described my invention, what I claim is—

An improved garrote or standing collar composed, substantially, of two counterpart plies, A and C, stitched together along their lower edges and around their ends, and a supplemental ply, B, having one longitudinal edge and a portion of each end stitched to the upper edge and part only of the ends of the ply A, and its other longitudinal edge and remaining portions of its ends stitched to the upper edge and part only of the ends of the ply C, said counterpart plies being united by a longitudinal line of stitches formed intermediate their top and bottom edges, whereby the supplemental ply is capable of being turned from side to side of the collar, if desired, substantially as described.

In testimony whereof I have hereunto set my hand in the presence of two subscribing witnesses.

A. CLARKE FELLOWS.
